UNITED STATES PATENT OFFICE.

ITALO ALFRED DE POLO, OF CONNELLSVILLE, PENNSYLVANIA.

SCREENING AND SEPARATING MACHINE

1,274,015.

Specification of Letters Patent. Patented July 30, 1918.

Application filed February 21, 1918. Serial No. 218,528.

To all whom it may concern:

Be it known that I, ITALO ALFRED DE POLO, a citizen of the United States, residing at Connellsville, in the county of Fayette, State 5 of Pennsylvania, have invented a new and useful Screening and Separating Machine; and I do hereby declare the following to be a full, clear, and exact description of the invention, such as will enable others skilled in 10 the art to which it appertains to make and use the same.

This invention relates to an improved screening and separating machine, particularly designed for use for screening or separating ashes, coal and the like, and one of the 15 objects of the invention is to provide a wheel supported portable frame, and a super-imposed frame, and means for revolving said super-imposed frame.

20 A further object of the invention is to provide means for digging the coal and ashes or the like, elevating the same and screening means adjacent the upper end of the elevating means, all of which being carried by 25 and mounted on said super-imposed revolving frame.

30 A further object of the invention is the provision of power means on the revolving frame for operating the various mechanisms carried thereby.

35 A further object of the invention is the provision of improved means connecting with the power means and a gear on the revolving frame, for revolving the frame at will in different directions.

In practical fields the details of construction may necessitate alterations falling within the scope of what is claimed.

40 The invention comprises further features and combination of parts as hereinafter set forth shown in the drawings and claimed.

In the drawings:—

45 Figure 1 is a view in side elevation of the screening and separating machine constructed in accordance with the invention.

Fig. 2 is a sectional view on line 2—2 of Fig. 1.

50 Fig. 3 is a sectional view on line 3—3 of Fig. 1, in fact showing the revolving frame removed.

Fig. 4 is a sectional view on line 4—4 of Fig. 1.

Fig. 5 is a sectional view on line 5—5 of Fig. 3.

55 Fig. 6 is a sectional view on line 6—6 of Fig. 3.

Referring more especially to the drawings, 1 designates the platform or bedplate of the portable frame, and which bedplate or platform is mounted upon the forward and rear 60 supporting wheels 2 and 3. The forward wheels 2 are mounted upon the front axle 4, the bolster 5 of which is pivotally connected at 6 by a king pin to the bolster 7, whereby the forward wheels may be turned in one 65 direction or the other for steering the machine from one place to another. Projecting downwardly from the platform or bedplate 1 or frame from each side portion substantially midway the ends of the frame 1 70 are brackets 8, which are substantially T-shaped and have their arms 9 secured at 10 to said frame. Brace rods 11 engage the crotches or notches 12 of the brackets 8, and the ends of said rods pass upwardly 75 through the frame 1 and have nuts 13 threaded thereon for holding the rods secure, and consequently bracing the frame. Mounted in suitable bearings 14 of the frame 1 is a shaft 15, on which the drums 16 are 80 mounted to rotate with the shaft. Suitable cables 17 are wound about the drums and have their ends secured at 18 to the drums. The other ends of the cables 17 are connected at 19 to the bolster 5 of the front 85 axle. A hand wheel 20 is keyed by means of a pin 21 to one end of the shaft 15, so that by rotating the wheel 20 in one direction or the other, the cables 17 (which are wound in opposite directions on the drums) 90 may be so operated to oscillate the axle 4, to swing the front wheels, whereby the machine may be guided to the right or the left. Mounted upon the bed frame or plate 1, 95 forwardly, rearwardly and near the sides thereof are plates 22, 23 and 24, which may be secured in any suitable manner as shown at 25. These plates are provided with elongated pockets 26, which are of the shape longitudinally and in cross section, as shown 100 clearly in Figs. 5 and 6, and are designed to receive the roller bearings 27, 28 and 29. It is to be noted, however, that the plates 24 are connected by the flanges 30, which are secured as at 31 to the longitudinal edges of 105 the base plate or frame 1. A frame 32 is superimposed on the frame 1, and comprises the forward and rear corner upright beams 33 and 34 and the side upright beams 35, all of which are mounted upon the base or platform 36. This super-imposed frame 32 is 110 movable to swing about a vertical axis, in

fact the frame may be oscillated or revolved in either direction of said vertical axis. The forward upright beams 33 have their upper ends braced relative to each other by the 5 beams 37, and the upper ends of the rear upright beams 34 are likewise braced by the beam 38. The longitudinal beams 39 connect the forward and rear upright beams 33 and 34, there being additional braces 40 for 10 reinforcing the structure of the frame 32. The base 36 of the frame 32 is suitably cut-away to provide the openings 41, to lighten said base. The frame 32 carries storage and delivering bins 42 and 43. Each bin is provided 15 with an upwardly extending V-shaped bottom 44, as shown clearly in Fig. 4, and also the forward and rear inclined plates 45. By these inclined plates and the inclined sides of the V-shaped bottom, the material 20 falling in the hoppers is divided toward each side and will easily empty from the openings 46, which are closed by the doors or closures 47 hinged at 48. The sides of the bin 42 extend completely to the top of 25 the frame 32. The base 36 of the frame 32 at its forward ends on its bottom is provided with bearing plates 49 the ends of which are bent and secured at 50 to the edges of the base 36. These plates 49 engage 30 the roller bearings 27 and 28. Secured by the screws 51 to the sides of the base 36 are the angle plates 52, which extend under the base 36 and engage the roller bearings 29. Arranged centrally of the base or frame 35 1 is a circular plate 53, which is secured by the screws 54 to the frame 1. This circular plate 53 is provided with radial pockets 55 for the reception of the roller bearings 56. Arranged on the top of the base 36 and 40 centrally thereof is a bevel gear 57 provided with a flange 58. A bearing plate 59 is arranged on the under surface of the base 36 and centrally thereof, so as to engage the bearing rollers 56. Suitable fastening means 45 or bolts 60 pass through the flange 58, the base 36 and the bearing plate 59 for securing said parts together. A bolt 61 passes through the gear 57, the base 36 through the circular plates 53 and 59, and through 50 the base or frame 1, and is provided with a nut 62, whereby said parts are united, so that the frame 32 may revolve on the frame 1. Mounted in suitable bearings 63 of the base 36 is a shaft 64 on one end of which 55 a beveled gear 65 is fixed so as to mesh with the bevel gear 57. Keyed by means of a feather 66 on the shaft 64 is a sleeve 67 and formed integral with the ends of this sleeve are bevel gear flanges or collars 68 and 69. One end portion of the sleeve 67 has an annular groove 70, in which the slip ring 71 is mounted. A lever, which is pivoted at 72 to the base 36, has its forks 73 connected to the pins 74 of the slip ring 65 or collar by means of the slots 75. A shaft 76 is mounted in bearings 77 of the base 36 and has fixed thereto a double bevel gear 78. A pulley 79 is also keyed to the shaft 76 to be engaged by the belt 80. When power is furnished to the double bevel gear 78 through the medium of said belt 80, and when one or the other of the bevel gear hollows or branches 68 and 69 is in mesh with the gear 78 by operating the lever 81, which is pivoted at 72, motion is imparted to the shaft 64. Since the gear 65 is meshing with the gear 57 the frame 32 may be revolved in one direction or the other. A shaft 82 is mounted in bearings 83 of the frame 32, and fixed on the shaft 82 are pulleys 84 and 85. The belt 80 passes about the pulley 84, and a belt 86 passes about the pulley 85. A suitable motor 87 is mounted on the forward end portions of the base 36, and its shaft carries a pulley 88, about which the belt 86 passes, thereby providing power for the shaft 82 which in turn furnishes power, whereby the frame 32 may be revolved in one direction or the other. A suitable conveyer frame 89 arranged on an incline is carried by the frame 32. The upper and lower ends of the conveyer frame respectively have shafts 90 and 91, provided with sprockets 92 and 93 about which the conveyer sprocket chain 94 passes. This conveyer sprocket chain is provided with conveyer buckets 95. The lower end of the conveyer frame 89 carries a suitable digger 96, similar to that set forth and illustrated in the application for a patent on a screening and separating machine, Serial Number 188,641, filed Aug. 28, 1917, in the name of I. A. De Polo. This digger and the conveyer combined constitute a mechanism, adapted to be directed, to gather or collect material and deliver the same to a combined agitator and screening device, to be herein-after set forth. Also mounted in the conveyer frame 89 (which is reinforced relative to the frame 32 by the braces 97) is a shaft 98, provided with the sprockets 99 and 100. A sprocket chain 101 (which engages and passes about the sprockets 102 on the shaft 82) passes about the sprocket 100. On the ends of the shaft 90 are sprockets 103 and 104. A sprocket chain 105 passes about the sprocket 104 and the sprocket 99, and since the shaft 82 is driven by the motor, it is to be observed that the elevating conveyer 94 is driven by the sprocket chains 101 and 105 and their connections. Mounted in bearings 106 on the top of the frame 32 is a shaft 107, on which the combined agitator and screening drum 108 is keyed. This agitator and screening drum is directly over the hopper or bin 42. The ashes, coal or the like that is conveyed upwardly by the conveyer is automatically dumped into the screening drum, by which the ashes, coal or the like is sieved, the finer particles pass 130

ing into the hopper or bin 42, the cinders or the large particles of the coal or the like passing out the end 109 of the drum into the hopper or bin 43. One end of the shaft 5 107 has a bevel gear 10. Mounted in a bearing 111 of the top of the frame 32 is a shaft 112 provided with a beveled gear 113 and a sprocket 114. A sprocket chain 115 passes about the sprocket 114 and the 10 sprocket 103, in view of which it will be seen that most motion is imparted to the screening drum receiving power from its connection with the upper shaft of the elevating conveyer, which in turn is driven by 15 the shaft 82. The digging device, the elevating conveying means, the screening mechanism and the hopper arrangement are all similar to the corresponding parts set forth and illustrated in the aforesaid pending application.

In the operation it is to be seen that by the provision of the belting or gearing between the driving motor with the vertical axis of the movable frame, and the clutch 25 connections, said movable frame may be easily and at will controlled, whereby said gathering and delivering mechanism may be directed toward different points or places of a dump. In fact the frame may be involved 30 entirely about its axis. By this construction the gathering and delivering mechanism may be moved to the rear part of the main frame, without turning the entire main frame about or backing it from the dump, 35 so as to direct the digger to the rear part of the side of the dump. For example in operating this machine, the operators may direct the machine, so as to make or wedge a cut into the dump of coal ashes or coke 40 ashes, and instead of backing the machine out from the cut entirely, it may be backed a short distance, then moved forwardly, and the movable frame swung entirely at right angles to the wheeled frame, and then the 45 digger or gathering mechanism may operate on the side of the cut in the dump. This gathering and delivering mechanism delivers the material to the combined agitator and screening device or drum, where it is agitated and screened into two different grades, 50 separately delivered into the storage and delivering bins 42 and 43 respectively.

The invention having been set forth what is claimed as new and useful is:—

1. In a material handling apparatus, a 55 portable supporting frame, a movable frame, a pivot shaft connecting the two frames, and about the vertical axis of which the movable frame may rotate, storage and delivering bins mounted upon and movable with said 60 rotating frame, an agitator and separator mounted upon said rotating frame and designed to deliver separately graded materials to said bins respectively, means movable with said rotating frame to collect and deliver material to be separated to said agitator and separator, operating means mounted upon and movable with the rotating frame to actuate said delivering and separating means, and a mechanism geared with 65 the operating means and said rotating frame for revolving said rotating frame, whereby said collecting means may be directed toward different points or places of a dump.

2. In a material handling apparatus, the 75 combination with a portable frame, of a movable frame to rotate on a vertical axis, means connecting the two frames whereby said movable frame may rotate on said axis 80 storage and delivering bins mounted upon and movable with said rotating frame, combined agitator and separator mounted upon the rotating frame and designed to deliver separately graded materials to said bins respectively, a mechanism movable with said 85 rotating frame and adapted to collect and deliver material to be separated to said agitator and separator, driving means mounted upon and movable with the rotating frame to actuate said mechanism and said separator, operative connections between the rotating frame and said driving means, whereby said rotating frame may be automatically 90 revolved to direct said mechanism to different places of a dump, and means for controlling said operative connections.

In testimony whereof I have signed my name to this specification in the presence of two subscribing witnesses.

ITALO ALFRED DE POLO.
